UNITED STATES PATENT OFFICE.

ROBERT S. BERGER, OF WANAKENA, NEW YORK.

FLANGER.

SPECIFICATION forming part of Letters Patent No. 792,876, dated June 20, 1905.

Application filed March 23, 1905. Serial No. 251,663.

To all whom it may concern:

Be it known that I, ROBERT S. BERGER, a citizen of the United States, residing at Wanakena, in the county of St. Lawrence and State 5 of New York, have invented a certain new and useful Flanger, of which the following is a specification, reference being had therein to the accompanying drawings.

This invention relates to flangers for scraping and clearing the rails of a railway road-bed of obstructing matter and other accumulation, such as ice, sleet, snow, &c.; and the object of the invention is to provide a complete flanger applicable to any car and in which 10 provision is made for permitting the shoes and their carriers to adjust themselves to the rails, the shoes being so mounted and their supporting connections so constructed and arranged that the shoes are yieldingly sus- 15 tained in operative position and allowed to rock forward and backward under pressure and also yield inwardly away from the rails, as occasion may require.

A further object of the invention is to make 20 the shoe-carriers reversible as to their angle, so that such angle may be changed to suit the direction in which the car is moving.

With the above and other objects in view, the nature of which will more fully appear as 25 the description proceeds, the invention consists in the novel construction, combination, and arrangement of parts, as herein fully described, illustrated, and claimed.

In the accompanying drawings, Figure 1 is a side elevation of a flanger embodying the 30 present invention. Fig. 2 is an end view of the same. Fig. 3 is a bottom plan view thereof. Fig. 4 is a cross-section on the line 4-4 of Fig. 1. Fig. 5 is a detail section showing 35 the key which holds the adjusting-plates.

Fig. 6 is a detail perspective view of one of the shoe-carriers and its adjusting-plate. Fig. 7 is a plan view of the shoe detached.

Like reference-numerals designate corre- 40 sponding parts in all figures of the drawings.

Referring to the drawings, 1 designates the bottom or floor of a car, and 2 the usual stringers extending lengthwise thereof, while 3 represents cross-beams extending transversely of

the car-bottom and to which the flanger of 50 this invention is secured.

Extending downward from the cross-beams 3 are end hangers 4, each having upper and lower cross-bars 5 and 6, respectively. A bed-plate 7 is supported at its ends under the 55 upper cross-bars 5 of said hangers and is further supported about centrally by an intermediate hanger 8, the bed-plate 7 being held by said hangers against vertical movement, but allowed to move endwise, so that the 60 flanger-shoes connected indirectly therewith may adjust themselves to the rails.

Beneath the bed-plate is a yielding support 9, consisting of a plate about the same size as the bed-plate and pressed downward by cushioning-springs 10, interposed between the bed-plate 7 and the yielding support, the ends of said support resting on the lower cross-bars of the hangers 4, as shown, and the downward movement of the support 9 being limited 70 thereby. Secured about centrally to the support 9 is a cross stop-cleat 11, the ends of which project so as to bring up against trusses or brackets 12 under the car-body, thus forming auxiliary means for limiting the downward movement of the support 9. The bed-plate 7 is also provided with pendent lugs or ears 13 at opposite sides, which have inturned lips 14, that enter notches 15 in the support 75 9 and project beneath the support adjacent to 80 the springs 10, thus affording additional means for limiting the degree of separation between the plate 7 and support 9. The plate 7 and support 9 are thus held from relative endwise movement, yet both may move endwise together between the upper and lower cross-bars 85 of the end hangers and also between vertical guide pins or bolts 16, connecting said upper and lower cross-bars.

Connected pivotally at 18 to the lower side 90 of the support 9 are adjustable pivot-plates 19. These plates are pivoted at their outer ends, the pivots being braced by straps 20, and the inner free ends of the plates enter between the support 9 and the stop-cleat 11, by 95 which they are held vertically, while capable of adjustment back and forth. The movable ends of the plates 19 are provided with

notches 21 to receive a removable key 22, which also passes through openings in the support 9 and cleat 11, the key and notches being so disposed that the plates 19 may be 5 swung either forward or backward, as indicated in Fig. 3, to suit the direction in which the car is moving and obtain the proper angular relation between the flanger-shoes and the rails.

10. Extending lengthwise of each plate 19 is a journal-pin 23, which forms a hinge-pin for the shoe-carrier, hereinafter described, and also a guide-pin, on which said carrier slides. The pin 23 is held in suitable bearings 24 on 15 the plate 19 and also passes through eyes or bearings 25 on the upper edge of a flanger-shoe carrier 26, which construction allows the carrier to rock forward and backward on the pin 23 and also to slide inward and outward 20 thereon, the carrier being urged outward with a yielding pressure by a spring 27, arranged behind the inner end of the carrier, as shown in Figs. 1 and 6. Each carrier 26 is sustained in a vertical position by means of springs 28, 25 located on opposite sides thereof and encircling a pin or bolt 29, which passes through a slot 30 in the carrier and connects the pendant arms 31 of a two-armed bracket 32, secured to the plate 19.
30. The carrier is formed with a recess or seat for a removable and reversible flanger-shoe 33, held in place by a pin or bolt 34, insertible in any of several holes 35 in the carrier, thus enabling the shoe to be adjusted in height. 35. The carriers are cut away or notched, as at 36, to fit over the heads of the rails, (shown at 37.)

It will be seen that the bed-plate and yielding support 9 and all parts connected therewith and carried thereby are bodily movable 40 transversely of the car-bottom to bring the shoes into proper relation to the rails; also, the shoes and their carriers may be set to incline forward, so that the shoes will drag 45 properly against the heads of the rails. It will also be seen that the carriers may rock back and forth and also slide inward and outward and that the carriers and shoes are sustained in their operative positions with a yielding 50 pressure. The shoes and carriers thus take care of themselves automatically and ride over switches, frogs, crossings, guard-rails, and other obstructions and are maintained at all times in correct relation to the rails to 55 scrape and clean the same.

Having described the invention, I claim—

1. A flanger comprising a bed-plate, a yielding support beneath the bed-plate, hangers in which said plate and support are mounted and 60 which limit the downward movement of the support, flanger-shoes connected with the yielding support, and springs interposed between the bed-plate and yielding support.

2. A flanger comprising a bed-plate, a yielding support beneath the bed-plate, end and intermediate hangers which hold the bed-plate fixed or immovable vertically and permit the support to yield, springs interposed between the plate and support, flanger-shoes carried by the support, a stop-cleat on the support, and a truss with which the stop engages and which forms auxiliary means to limit the downward movement of the yielding support. 65

3. A flanger comprising a bed-plate, a yielding support beneath the bed-plate, stops on 75 one of said members for limiting the downward movement of the yielding support, hangers for the bed-plate, springs interposed between the bed-plate and yielding support, and flanger-shoes carried by the yielding support. 80

4. A flanger comprising a bed-plate, a yielding support beneath the bed-plate, hinged shoe-carriers connected with said support, springs for permitting said carriers to yield and swing, and reversible flanger-shoes de- 85 tachably connected with the carriers.

5. A flanger comprising a bed-plate, a yielding support beneath the bed-plate, a hinged shoe-carrier connected with said support, a 90 bracket with arms lying on opposite sides of the carrier, and springs interposed between the carrier and bracket-arms.

6. A flanger comprising a bed-plate, a yielding support beneath the bed-plate, a hinged shoe-carrier connected with said support, a 95 bracket with arms lying on opposite sides of the carrier, a bolt connecting the bracket-arms and passing through the carrier, and springs encircling said bolt between the carrier and bracket-arms. 100

7. A flanger comprising a bed-plate, a yielding support beneath the bed-plate, a hinged spring-sustained shoe-carrier connected with said support and adapted to yield forward and backward, and means for urging said carrier 105 outward toward the rail with a yielding pressure.

8. A flanger comprising a bed-plate, a yielding support beneath the bed-plate, a shoe-carrier, a combined hinge and guide pin on which the carrier is mounted, and springs which sustain the carrier in operative position and allow the same to swing on said pin as a journal and slide on the pin as a guide, for the purpose set forth. 110

9. A flanger comprising a bed-plate, a yielding support beneath the bed-plate, adjustable plates connected to the lower side of the yielding support, shoe-carriers connected to said adjustable plates so as to yield, and means for fastening said adjustable plates when adjusted. 120

10. A flanger comprising a bed-plate, a yielding support beneath the bed-plate, adjustable plates connected to the yielding support, shoe-carriers connected to the adjustable plates and mounted to yield in accommoda- 125

dating themselves to the rails, and means for fastening the adjustable plates in such positions as to hold the shoe-carriers at an angle either forward or back of a line transverse to the movement of the car.

11. A flanger comprising a slideable bed-plate, a yielding support beneath the bed-plate, springs interposed between the bed-

plate and support, and spring - sustained flanger-shoes carried by the yielding support. ¹⁰

In testimony whereof I affix my signature in presence of two witnesses.
